DESIGN FOR A CLOCK CASE OR SIMILAR
ARTICLE

Louis Rogow, Hartford, Conn.

Application June 2, 1933. Serial No. 48,258

Term of patent 7 years

To all whom it may concern:

Be it known that I, Louis Rogow, a citizen of the Union of Soviet Russia, residing at Hartford, in the county of Hartford and State of Connecticut, have invented a certain new, original, and ornamental Design for Clock Cases or Similar Articles, of which the following is a specification, reference being had to the accompanying drawing forming a part thereof, and of which Figure 1 is a view in front elevation, and Figs. 2 and 3 are views in side elevation of a clock case or similar article.

I claim:

The ornamental design for a clock case or similar article substantially as shown.

LOUIS ROGOW.
